DESIGN FOR A COMBINED GRAVE PROTECTOR AND MARKER

George Oscar Sullivan, Pampa, Tex.

Application September 16, 1937, Serial No. 71,649

Term of patent 14 years

To all whom it may concern:

Be it known that I, George Oscar Sullivan, a citizen of the United States, residing at Pampa, in the county of Gray and State of Texas, have invented a new, original, and ornamental Design for a Combined Grave Protector and Marker, of which the following is a specification, reference being had to the accompanying drawing, forming part thereof.

Figure 1 is a plan view of a combined grave

I claim:

The ornamental design for a combined grave protector and marker, as shown.

GEORGE OSCAR SULLIVAN.
